C. I. LONGENECKER.
INTERNAL COMBUSTION ENGINE.
APPLICATION FILED DEC. 7, 1907.

908,112.

Patented Dec. 29, 1908.

UNITED STATES PATENT OFFICE.

CHARLES I. LONGENECKER, OF MILWAUKEE, WISCONSIN, ASSIGNOR TO INTERNATIONAL HARVESTER COMPANY, A CORPORATION OF NEW JERSEY.

INTERNAL-COMBUSTION ENGINE.

No. 908,112.

Specification of Letters Patent.

Patented Dec. 29, 1908.

Application filed December 7, 1907. Serial No. 405,536.

To all whom it may concern:

Be it known that I, CHARLES I. LONGENECKER, a citizen of the United States, residing at Milwaukee, in the county of Milwaukee and State of Wisconsin, have invented a new and useful Improvement in Internal-Combustion Engines, of which the following is a complete specification.

This invention relates to means for properly effecting the vaporization and mixing of the charge before being introduced into the combustion chamber, and is designed more particularly for application to engines using low gravity oils, such as kerosene and crude oil.

The object in view is to secure a more perfect mixture and combustion of the charge, and hence a higher fuel efficiency, and also to overcome the severe shocks or concussions usually attending the use of heavy oils in explosive engines.

The results above mentioned are largely secured by readmitting a relatively small portion of the exhaust gas to the combustion chamber and utilizing this portion so readmitted both to draw in and to heat the oil for the charge.

The preferred construction of the improvement is illustrated in the accompanying drawings, in which—

Figure 1 represents a rear view of the cylinder of an engine with the improved vaporizer appearing partially in side elevation and partly in section in connection therewith.

Fig. 2 is a side view of the rear end of the cylinder with the vaporizer appearing in end elevation. Fig. 3 is a cross section of the air inlet pipe, taken on the line 3—3 of Fig. 1. Fig. 4 shows a fragmentary longitudinal section of the discharge end of the heating chamber, the view being taken as indicated by the line 4—4 in Fig. 2; and Fig. 5 is a detail showing the pan in which is burned the oil for heating the mixing chamber in starting.

Referring to the several figures, the cylinder, only a portion of which is shown, is designated by 1.

2 designates the exhaust pipe, and 3 the passageway through which the air and fuel are conducted to the combustion chamber. That portion of the passageway 3 which lies adjacent to the cylinder 1 constitutes the mixing chamber 4. A nozzle 5 is located in the mixing chamber, said nozzle communi-

cating, through the vertical channel 6 and the transversely extending channel 6¹, (see Fig. 2) with the laterally disposed, constant level cup 7. The supply and overflow pipes 8 and 9, respectively, lead from the cup to an oil supply tank, which is not shown.

A heating chamber 10 is interposed in the exhaust pipe 2, and the exhaust channel thereof in effect constitutes a portion of the said exhaust pipe. The heating chamber 10 comprises the interior channel 11 for the exhaust gases which enter therein through the pipe 2 and discharge therefrom through a continuation 2¹ of said exhaust pipe. Surrounding the exhaust channel 11 is a casing 12 inclosing the passageway through which the air is admitted to the heating chamber. The longitudinally extending walls 13, which terminate a short distance from the forward end of said heating chamber 10 and are arranged on either side thereof (see Figs. 1 and 2), divide the said passageway into a lower channel 14, through which the air enters, and an upper channel 15, through which the air returns, as indicated by arrows in Fig. 1, and flows to the cylinder through the air passageway 3 and mixing chamber 4.

At the air inlet end of the heating chamber 10, and preferably formed integral therewith, is an air channel 16, which communicates directly with the air and fuel passageway 3. A two-way plug valve 17 is arranged near the mouth 16¹ of the channel 16, and this plug valve is adapted to divert the incoming current of air either through the channels 14 and 15 of the heating chamber, or by-pass it through the chamber 16 direct to the air passageway 3. When the handle 17¹ of the plug valve 17 occupies the position indicated by full lines in Fig. 1, the air will be directed through the heating chamber 10, but when in the position indicated by dotted lines in the same figure, the air will be made to pass direct to the cylinder without being heated, as is frequently desirable when operating inside a building or in hot weather. In a similar manner the plug valve 2¹ is arranged to divert either a portion or all of the exhaust gases through the exhaust channel 11 of the heating chamber 10, or direct to the continuation 2¹ of the exhaust pipe 2.

The inflow of oil through the nozzle 5 is regulated by means of the needle valve 18, which is provided at its outer end with

the milled thumb nut 18¹. The amount of oil drawn from the nozzle 5 by the air current which flows through the passageway 3 is supplemented by an additional 5 amount drawn from said nozzle, by means of a jet of exhaust gas which is directed thereagainst. A conduit 19 leads from the interior of the exhaust gas channel, or chamber, 11 to a point closely adjacent 10 to the nozzle 5, as clearly shown in the several figures. A jet of the hot exhaust gases is thus projected against and over the nozzle, heating the same as well as the oil drawn therefrom, thus securing a much 15 better spraying effect. The entrance of the exhaust gases through the conduit 19 to the mixing chamber occurs simultaneously with the exhaust from the combustion chamber. This jet of exhaust gas is mixed 20 with the oil it draws in and the hot mixture of inert gas, saturated with oil, fills the air passageway as well as the mixing chamber and imparts heat to the inclosing walls. The succeeding aspiratory stroke of the 25 engine will first draw in this mixture of exhaust gas and oil, which will be followed by fresh air and oil. The charge is thus formed of two parts, viz., that initially introduced into the combustion chamber, 30 and consisting of exhaust gas and oil, and that following, which constitutes the main portion of the charge and consisting of hot air and oil. The introduction, initially, of this hot but inert exhaust gas mixed 35 with oil, operates to prevent pre-ignition, serves to keep the fuel passageway and mixing chamber hot, and results in a charge being formed which will burn clean and without producing what is termed explosion 40 waves during the working stroke of the engine. Only a relatively small portion of the exhaust gas is readmitted to the combustion chamber, but it dilutes the charge, the combustion is less rapid and the violence 45 of the shocks is mitigated.

Instead of the conduit 19 extending laterally from the exhaust pipe, it is made to lead from an abutting surface therein against which the gas impinges, and hence 50 a more forcible jet is obtained. Such abutting surface is here formed by the end 11¹ of the chamber or channel 11.

In order to start the engine with kerosene, the air passageway is heated by burning oil or other combustible material in the pan 21, which can be detachably secured to the mouth 16¹ of the air inlet by means of the straps 22 fixed thereon, as shown by dotted lines in Fig. 1 the plug 55 20¹ of the vent 20 being removed. The vent 20 is provided in the wall of the mixing chamber between said nozzle and the combustion chamber, and is normally closed by means of the plug 20¹. This vent is 60 open to allow the flames to pass through

and heat said mixing chamber, and since the said vent lies beyond the nozzle 5, the flames will be made to pass the same and heat the oil therein. By thus heating the walls of the mixing chamber and the nozzle 70 which contains the oil used to form the initial charge, the engine can be started without difficulty on kerosene.

What I claim as my invention, and desire to secure by Letters Patent, is:

1. In an internal combustion engine, in combination, a combustion chamber, an exhaust pipe leading therefrom, a vertically disposed fuel passageway through which the charge is admitted to the combustion 80 chamber, a mixing chamber located therein, an oil nozzle located in said mixing chamber, a vent normally closed but adapted to be opened when starting the engine, said vent formed in the wall of said mixing chamber 85 at a point between the nozzle and said combustion chamber, and detachable means adapted to be secured to the mouth of said fuel passageway for receiving combustible material employed to heat the air inlet and 90 mixing chamber in starting the engine.

2. In an internal combustion engine, in combination, a combustion chamber, an exhaust pipe leading therefrom, a fuel passageway through which the charge is admitted to the combustion chamber, a mixing chamber located therein, an oil nozzle located in said mixing chamber, and a conduit connecting the said exhaust pipe and mixing chamber for readmitting a 100 relatively small portion of the exhaust gas to the combustion chamber, said conduit terminating in the mixing chamber adjacent to the nozzle and in position to direct the hot exhaust gas thereagainst.

3. In an internal combustion engine, in combination, a combustion chamber, an exhaust pipe leading therefrom, an air heating chamber interposed in said exhaust pipe and provided with an air and an exhaust channel, the latter constituting a portion of the exhaust pipe, a mixing chamber communicating with said combustion chamber and with said air heating chamber, an oil nozzle located in the mixing 110 chamber, a valve for admitting either a portion or all of the air into the heating chamber or direct to the mixing chamber, and a conduit connecting the exhaust channel of the heating chamber with the 115 mixing chamber for readmitting a portion of the exhaust gases to the combustion chamber.

4. In an internal combustion engine, in combination, a combustion chamber, an exhaust pipe leading therefrom, an air heating chamber interposed in said exhaust pipe and provided with an air channel and an exhaust channel, the latter constituting a portion of the exhaust pipe, a mixing 120 125

chamber leading to the combustion chamber and communicating with the heating chamber, and also with the outer air, an oil nozzle located in the mixing chamber, a valve for introducing either a portion or all of the air through the air channel of the heating chamber or direct to the mixing chamber, a separate valve for admitting either a portion or all of the exhaust gases into the exhaust channel of the heating chamber, and a conduit connecting the exhaust channel of the heating chamber with the mixing chamber for readmitting a portion of the exhaust gases to the combustion chamber.

5 5. In an internal combustion engine, in combination, a combustion chamber, an exhaust pipe leading therefrom, an abutment in said exhaust pipe against which the exhaust gases impinge, a fuel passageway through which the charge is admitted to the combustion chamber, a mixing chamber located 35 therein, an oil nozzle in said mixing chamber, and a conduit connecting the said exhaust pipe and fuel passageway for readmitting a relatively small portion of the exhaust gas to the combustion chamber, said conduit 40 leading from the abutment in said exhaust pipe and terminating in the mixing chamber adjacent to the said oil nozzle and in position to direct the hot exhaust gas thereagainst.

10 20 25

mixing chamber, and a conduit connecting the exhaust channel of the heating chamber with the mixing chamber whereby a relatively small portion of the exhaust gas is readmitted to the combustion chamber and operates to draw oil from the nozzle.

6. In an internal combustion engine, in combination, a combustion chamber, an exhaust pipe leading therefrom, an abutment in said exhaust pipe against which the exhaust gases impinge, a fuel passageway through which the charge is admitted to the combustion chamber, a mixing chamber located 40 therein, an oil nozzle in said mixing chamber, and a conduit connecting the said exhaust pipe and fuel passageway for readmitting a relatively small portion of the exhaust gas to the combustion chamber, said conduit 45 leading from the abutment in said exhaust pipe and terminating in the mixing chamber adjacent to the said oil nozzle and in position to direct the hot exhaust gas thereagainst.
